UNITED STATES PATENT OFFICE

2,664,507

SIMPLIFIED ELECTRICALLY STEERABLE
ANTENNAFrank Mural, Drexel Hill, Pa., assignor to Radio
Corporation of America, a corporation of Dela-
ware

Application February 1, 1950, Serial No. 141,617

2 Claims. (Cl. 250—33.55)

1

The invention relates to antennas and it particularly pertains to antennas for TV receivers which can be oriented easily for optimum results and particularly for minimizing ghost images in television reception.

It has been suggested for the latter purpose that antenna arrays of the conventional type be made mechanically rotatable, but such an arrangement is too complicated and expensive for widespread usage. Since a fixed antenna array does not require nearly the mechanical strength of a rotatable array, a means of obtaining a steerable antenna field pattern with fixed antenna elements is extremely desirable, but electrically steerable antennas known to the prior art are in general large complex multi-element arrangements entirely unsuited for use with television receivers used in the average home.

It is an object of the invention to provide an improved electrically steerable antenna of extremely simplified construction, having substantially fixed components, for television receiver installations such as are encountered in the average home.

It is another object of the invention to provide a highly simplified electrically steerable antenna capable of installation within the housing of a receiver or auxiliary cabinet structure and using components readily available for other purposes.

It is a more specific object of the invention to provide a plurality of angularly arranged antenna elements, to provide optimum performance in discreetly fixed directions together with means providing continuous variation of the directivity of the overall antenna pattern.

These and other objects of the invention which will appear as the specification progresses are attained by means of an antenna system comprising a plurality of antenna elements oriented in different directions from each other and interconnected by transmission line means to a variable resistance element, the movable contacts of which are connected in turn to a radio frequency transducer, for example, a television receiver.

Several embodiments of the invention will be described with reference to the accompanying drawing forming a part of the specification and in which:

Fig. 1 is an arrangement of a steerable wide-band antenna according to the invention;

Fig. 2 is an illustration of an alternate embodiment of the antenna system according to the invention; and

Figs. 3 and 4 are illustrations of specially constructed transmission lines suitable for incorpo-

2

ration in arrangements according to the invention.

Referring to Fig. 1, there is shown an antenna arrangement which comprises four conductors, 12—15, arranged in radial relationship to each other at a central point, and connected in pairs 12—13 and 14—15 to conductors 22—23 and 24—25 respectively, which conductors constitute transmission lines over which radio frequency energy induced in conductors 12—15 is translated to a variable resistor device 27, having a resistance element 29, and two simultaneously rotatable arms 31—32 to which transducer apparatus (not shown) may be connected by means of a conventional transmission line 35. The resistance element may consist of a 360° carbon potentiometer with four symmetrically spaced taps to which conductors 22—25 are connected and two insulated opposing arms 31—32, or two ganged center-tapped potentiometers connected in equivalent fashion, the former being shown rather schematically for clarity of description. It will be necessary to provide terminal blocks for the transmission lines at both ends to prevent variation in the relative lengths of the transmission line wires on installation.

Alternatively, the antenna portion of the system may consist of crossed dipoles (at 90°), or folded dipoles, or, if the desired direction of reception is limited to within 90°, dipoles with reflectors. The transmission line should be constructed for the required impedance, low loss and take a form suitable to low-cost manufacture.

An example of alternate construction is shown in Fig. 2, wherein conductors 12—15 have been replaced with triangular metal sheets 52—55 in order to provide a wider frequency band response. Alternatively, wires arranged to define the edges of each sheet would serve as well or an arrangement such as described in U. S. Patent 2,175,253 issued October 10, 1939 to P. S. Carter would also be suitable. Two ganged center-tapped potentiometers 58 and 59 are connected together to effect a resistance ring as in the embodiment shown in Fig. 1. Opposite ends of potentiometers 58 and 59 are connected to leads 22 and 23 and the center taps of potentiometers 58 and 59 are connected to leads 24, 25 respectively. The arms 61, 62 are connected to a transducer by means of a length of transmission line 35 as before. Thus when the arms 61, 62 are at the end of travel substantially all of the signal induced in dipoles 52—53 is directed to the transducer and when they are at the center of travel substantially all of the signal from dipoles 54—55

is directed to the transducer. At intermediate points the transducer is supplied with proportionate signal voltages from both sets of dipoles.

From an inspection of the drawing it is evident that the antenna system according to the invention is equally applicable to outdoor installations or incorporation in the cabinet of the receiving device. In the latter case it may be necessary to bend the ends of the conductors 12-15 and 52-55. The potentiometer can be conveniently arranged to be controlled from the front panel of the receiver as will be obvious to anyone familiar with the art.

In most installations it will be desirable to use standard 300 ohm transmission lines so that resistor element 27 will preferably have a resistance of 300 ohms between taps and potentiometer 58 and 59 will have a resistance of 600 ohms end-to-end. Two twin-conductor transmission lines can be used for conductors 22-23 and 24-25, although a four conductor transmission line of the type having a cross section as shown in Fig. 3 has several obvious advantages. A considerably better type of four-wire transmission line arrangement is shown in cross-section in Fig. 4. In both the arrangements of Figs. 3 and 4, the maximum field between conductors 22-23 and 24-25 is substantially in air and not dielectric material. The arrangement of Fig. 4 can be made as sturdy as that of Fig. 3 by judicious dimensioning of the webbing while at the same time being much easier to extrude in manufacturing. The tapering of the webbing provides the necessary strength and rigidity without requiring the use of an excessive amount of insulating material. The X-shaped cross-section of the transmission line arrangement of Fig. 4 is much less susceptible to deleterious effects of dust and moisture collecting on the surface of the insulation since the extraneous matter is not in the region of maximum field.

Conventional tuning and/or impedance matching elements may, of course, be interposed between the antenna and the transmission line.

While the invention has been described in terms of specific embodiments, it is to be understood that other arrangements and modifications will be suggested to one skilled in the art without departing from the spirit and scope of the invention.

The invention claimed is:

1. A steerable antenna system having a pair of colinear energy receiving elements each hav-

ing two centrally located electric terminals for connecting to a transmission line, a four terminal resistive mesh network, and a transmission line comprising an elongated dielectric member of substantially cruxiform cross section and two pairs of conductors embedded in said dielectric member, each conductor being located in an arm of the cruxiform structure, the conductors of each pair of said conductors being reconnected individually at one end to said receiving elements and at the other end to alternate terminals of said resistive mesh network.

2. A steerable antenna system comprising two center-fed dipole antennas constituted by pairs of triangular conductive surface elements arranged in cruxiform relationship in a substantially single plane, a pair of potentiometers having fixed end terminals, intermediate fixed taps and variable contacts ganged to be adjusted simultaneously, means to connect the end terminals of said potentiometers effectively to form a resistance ring, means to connect the adjacent ends of a pair of oppositely disposed conductive surface members individually to the oppositely disposed intercoupled end terminals, means to connect the adjacent ends of the remaining pair of said conductive surface elements to said intermediate fixed taps, said means comprising a pair of two-conductor transmission lines having a common webbing of insulating material of cruxiform cross section maintaining the conductors of said line in fixed spaced relationship, and means to connect radio transducer apparatus to said variable contacts of said potentiometer.
